(57) **CLAIM**

The ornamental design for an intelligent lampholder, as shown and described.

DESCRIPTION

FIG. 1 is a front elevational view of an intelligent lampholder showing my new design;

FIG. 2 is a left side view thereof;

FIG. 3 is a right side view thereof;

FIG. 4 is a top plan view thereof;

FIG. 5 is a bottom plan view thereof;

FIG. 6 is a perspective view thereof; and,

FIG. 7 is another perspective view thereof.

The broken lines shown the drawings illustrate portions of the intelligent lampholder that form no part of the claimed design.

1 Claim, 7 Drawing Sheets
